ROTARY MACHINE

**David M. Smith, Hermosa Beach, Calif., assignor
to Emsco Derrick & Equipment Company, Los
Angeles, Calif., a corporation of California**

Original application June 3, 1931, Serial No.
541,771. Divided and this application February
13, 1933, Serial No. 656,603

17 Claims. (Cl. 255—23)

My invention relates to rotary machines of the character employed in the drilling of oil wells by the so-called rotary system. This application is a division of my application entitled Oil enclosed rotary, Serial No. 541,771, filed June 3, 1931.

The invention contained herein relates particularly to a novel rotary table guard which accomplishes the very important new result of preventing rotary mud, slush, or the like, which falls onto the rotary table during the ordinary operation of the rotary machine, from being thrown outwardly a material distance beyond the rotary table and onto the floor of the derrick. The invention also relates to a novel sealing means which prevents oil employed for lubricating purposes from being thrown from or escaping from an enclosed portion of the rotary machine. In addition, the invention relates to means for preventing foreign matter from entering the enclosed portion. In order that my invention may be fully and clearly understood, I will briefly refer to that part of the oil well drilling industry to which my invention appertains.

In the industry referred to, the rotary machine is placed on the derrick floor of the well being drilled. A drill pipe is extended through the rotary table of the rotary machine and carries a bit at its lower end. In the present form of rotary machine the rotary table has a bevel or ring gear which is driven by a pinion mounted on a pinion shaft, which pinion shaft is journaled in bearings supported by the base of the rotary machine. A sprocket is ordinarily secured to the outer end of the pinion shaft, which sprocket is driven from a draw works ordinarily positioned at the side of the derrick floor by means of an endless chain which extends across the derrick floor. The rotary table of the rotary machine rotates the drill pipe and the bit digs away the bottom of the well in order to deepen same. The drill pipe is usually carried by a swivel head which is in turn supported by a travelling block for the purpose of feeding the drill pipe downwardly into the well as drilling progresses. For the purpose of providing lubrication for the bit, for floating the drill pipe away from the walls of the well being drilled, for preventing cave-ins in the well, and for carrying the cuttings to the surface of the ground, rotary mud is pumped downwardly through the drill pipe, which rotary mud passes outwardly through openings provided in the bit and flows up to the surface of the ground around the drill pipe.

When adding a length or section of drill pipe

or removing a length or section of drill pipe, considerable rotary mud which is very slushy and slippery in its character falls onto the rotary table, and in present rotary machines when the rotary table is rotated either to make or break a joint, this rotary mud is thrown outwardly from the table of the rotary machine by centrifugal force and is spread over the derrick floor. Obviously, this rotary mud on the derrick floor makes footing very insecure and creates a constant menace to the safety of the operators working near the rotary machine or working on the floor of the derrick.

It is an object of my present invention to provide a rotary machine of the type above described in which rotary mud is not thrown outwardly onto the floor of the derrick.

It is a further object of my invention to provide a rotary machine having a means which prevents the rotary mud falling onto the rotary table from being thrown outwardly a material distance beyond the rotary machine.

It is a more specific object of my invention to provide a rotary machine of this character which has a guard means which is so formed that the rotary mud or mud fluid thrown outwardly from the upper surface of the rotary table during rotation is deflected downwardly so that the same is not thrown over the derrick floor.

It is a further object of my invention to provide a guard means of the character referred to in the foregoing paragraph which includes as a part thereof a means for depriving the rotary mud which is thrown outwardly from the rotary table of its centrifugal or swirling motion in order that the same will fall directly downwardly and will not pass outwardly over the derrick floor.

It is a still further object of my present invention to provide a rotary machine having a stationary guard which partially covers the top of the rotary table and which serves as a platform upon which a workman may stand if necessary.

Oil wells today are being drilled to exceedingly great depths, necessitating larger and heavier drilling apparatus which consequently materially increases the already tremendous strains to which rotary machines are subjected during operation. As a result, the working parts of the rotary machines have been made more and more rugged and massive in order to endure these strains and consequently a necessity has arisen for suitable lubrication of these working parts in order to minimize friction and reduce wear.

It is therefore an object of this invention to provide a rotary machine in which all of the

working parts are completely enclosed and constantly lubricated.

In the preferred form of my invention there is a lubricant chamber which is formed by cooperating walls of the base and the rotary table of the rotary machine. This lubricant chamber contains a lubricant, such as oil, which is circulated through the working parts. In order to reduce oil leakages, it is highly desirable to have 10 suitable sealing means provided and particularly at the joint between the base and the rotary table.

It is therefore an object of this invention to provide a unique sealing means for preventing lubricant from leaking or being thrown outwardly from the lubricant chamber of the rotary machine.

The rotary mud or fluid which falls onto the top of the rotary table, as previously mentioned, in ordinary rotary machines finds its way into 20 the working parts and causes undue wear and destroys the lubricating qualities of any such lubricant as may be provided. In the rotary machine of my invention it is highly desirable to provide special means for excluding rotary mud 25 from the lubricant chamber and to protect the oil therein from being adulterated.

It is one of the objects of this invention to provide a rotary machine of the type described above in which there is provided sealing means 30 for preventing rotary mud or mud fluid from entering the interior of the rotary machine.

Other objects and particular advantages of the invention will be brought out in the following description of the preferred form of my invention.

Referring to the drawings,

Fig. 1 is an elevational view, partly sectioned, showing the features of my invention.

Fig. 2 is a plan view of Fig. 1.

Fig. 3 is an enlarged fragmentary view showing that portion of the rotary machine particularly incorporating the features of my invention and taken as indicated by the line 3-3 of Fig. 2.

Fig. 4 is a fragmentary plan view of the rim portion of the base of the rotary machine.

Fig. 5 is a fragmentary sectional view taken as indicated by the line 5-5 of Fig. 2.

Referring to the drawings and particularly Figs. 1, 2 and 3, the numeral 11 represents a base which is provided with a horizontal wall 13 from which skids 14 depend. Formed integrally with the horizontal wall 13 adjacent one end thereof is a vertically extending annular wall 16, this wall being of a diameter substantially equal to the width of the horizontal wall 13. Adjacent its upper edge the annular wall 16 is increased in thickness and is cored to form an annular rim 17 having a series of vertical passages 18 extending from the upper edge 19 of the wall 16 to the lower edge 20 of the rim 17. Formed also integrally with the wall 13 is a vertically extending annular rim 22 which is somewhat smaller in diameter than the annular wall 16 and cooperates with this wall 16 and the horizontal wall 13 to form an oil reservoir 23. The wall 13 is somewhat lower than the wall 16 and is somewhat thicker in order to either support or form a bearing race 25 of a main table bearing 26. The main table bearing 26 includes rollers 27 and an upper movable race 28 which may be separate or may be formed integrally with a rotary table 29 which is supported by the base. This rotary table 29 has a cylindrical wall 30 which extends downwardly through a central opening 31 of the base 11 and also includes a horizontally

extending flange which forms a table top 44 of the rotary table 29. The table top 44 has secured to the under side thereof and within the rim 17 a bevel gear or ring gear 46 having downwardly facing bevel teeth 47. The ring gear 46 has an internal diameter slightly greater than the outer diameter of the bearing 26 and an external diameter slightly less than the internal diameter of the annular wall 16. For the purpose of rotating the rotary table 44 there is a 10 pinion 48 having teeth 49 which are meshed with the teeth 47 of the ring gear 46. This pinion 48 is supported within the oil reservoir 23. The lower portion of the pinion is submerged below the oil level in order that oil will be picked 15 up by the pinion 48 and delivered to the teeth 47 of the ring gear 46. The pinion 48 is secured to a pinion shaft 50 which extends outwardly through an opening provided in the wall 16 and is rotatably supported by bearings 51 which include suitable bearing housings, as shown. The outer end of the pinion shaft 50 has a sprocket 52 secured thereto whereby the pinion shaft 50 may be rotated.

Between the wall 16 of the base 11 and the table top 44 is a mud seal generally designated by the numeral 53 and disclosed best in Fig. 3. The seal 53 includes an annular groove 54 formed in the upper edge 19 of the wall 16, this groove providing an inner upwardly extending lip 55 and an outer upwardly extending lip 56. The groove 54 extends through and communicates with the vertical passages 18. Formed on the under surface of the table top 44 is a depending annular ridge 57 which extends downwardly into the groove 54. The inner vertical annular surface 58 of the ridge 57, the horizontal under surface of the table top 44, and the outer vertical annular surface of the ring gear 46 cooperate with the inner lip 55 to form an annular passage 40 59 between the bottom of the groove 54 and the interior of the base casting 11, this passage 59 in cross section having the form of an inverted U. Formed on the periphery of the table top 44 is a depending annular flange 60 providing an inner vertically extending annular surface 68 which cooperates with the under surface of the table top 44, the outer vertical annular surface 69 of the ridge 57, and the upwardly extending outer lip 56 to form a narrow annular passage 70 communicating between the bottom of the groove 54 and the exterior of the rotary machine, this passage 70 in cross section also having the form of an inverted U, as shown. Provided adjacent the mud fluid seal 53 is an oil saving means or oil seal generally designated by the numeral 73 shown best in Fig. 3. Provided on the periphery of the ring gear 46 is an outwardly extending flange 76, the under surface of which is formed to provide a depending annular bead 76. Formed on the inner surface of the wall 16 directly below the bead 76 is an annular shoulder 77 in the upper edge of which is formed an annular trough 78. The bead 76 overhangs the trough 78 in the manner shown so that the same is in overlapping relation thereto. Provided in the shoulder 77 is a series of vertical drain openings 79 extending from the trough 78 to the lower surface of the shoulder 77.

For the purpose of preventing rotary mud or mud fluid from being thrown outwardly from the rotary table 29 over the derrick floor by centrifugal force and as a means of guarding workmen from possible injury, I provide a ring guard 80 which comprises a flanged ring pro-

viding a vertically extending annular wall 91 which surrounds the periphery 92 of the upper portion of the rotary table 29, and a horizontally extending flange or plate 93 which extends inwardly from the annular wall 91 and is preferably formed integrally therewith. For the purpose of securing this ring guard 90 in place, a plurality of bolt means 95 is employed, as disclosed in detail in Fig. 3. The ring guard 90 is supported in such a manner as to provide a slight clearance or small space, as indicated at 97, between the outer portion 98 of the top face of the rotary table and the lower face 99 of the horizontal plate or flange 93. The horizontal plate or flange 93 is annular in character and therefore provides a relatively large central opening which exposes a large part of the upper face of the rotary table 29 and gives full access to the rotary table to permit usual drilling operations, etc. to be performed with the rotary machine. The annular wall 91 is of such a diameter that there is an annular space 102 of substantially vertical extension surrounding the peripheral wall 92 of the rotary table 29 and within 25 an inner face 103 of the annular wall 91. The outer part of the clearance or space 97 is connected to the annular space 102, as shown clearly in Fig. 3.

Projecting inwardly from the inner face 103 of the vertical annular wall 91 is a plurality of radially spaced fins 106 which are preferably of vertical extension. These fins 106 are most conveniently formed integrally with the annular wall 91, and in the preferred form of my invention 35 they are extended inwardly to a point just short of the peripheral wall 92 of the rotary table 29.

The operation of my invention is substantially as follows:

The table 29 is rotated by means of a sprocket 40 chain, not shown, which engages the sprocket 52. This rotates the pinion shaft 58 and the pinion 48. Due to the fact that the pinion 48 has teeth in engagement with the teeth 47 of the ring gear 46, the rotary table is rotated. Due to the fact 45 that the pinion 48 is partly submerged in the oil in the oil reservoir 23, it will pick up a quantity of oil and carry it into contact with the teeth 47 of the ring gear 46. A portion of the oil adhering to the teeth 47 of the ring gear is 50 thrown outwardly by centrifugal force against the inner surface of the wall 16 and will thereafter flow downwardly into the oil reservoir 23, a part of this oil being utilized to properly lubricate the main bearing 26. Any of the fluid adhering to the teeth 47 of the ring gear which 55 might be caused by centrifugal force to travel directly outwardly along the teeth and tend to flow upwardly through the passage 59, as indicated by the arrows D, is caught by the depending bead 76 and is delivered thereby by centrifugal force to the trough 78 where the oil may collect and from which the oil drained through the openings 79, flowing, as indicated by arrows E, downwardly along the annular wall 16 will pass to the 60 oil reservoir 23.

When the rotary machine is in operation and the rotary table is rotated it will rotate in a clockwise direction in Fig. 2, as indicated by the arrow R. Any rotary mud or mud fluid which 65 falls onto the rotary table either while the same is at rest or while the same is rotating will be thrown outwardly with considerable force upon rotation of the rotary table in paths substantially tangential to the periphery of the rotary table such as is indicated by the arrows 108 of

Fig. 2. It is quite common during the course of drilling of an oil well for a rotary table to be driven at speeds ranging from 100 to 140 revolutions per minute, and I have determined from observation that the force at which the rotary mud and mud fluid or water are thrown outwardly from the rotary table is so great that the rotary mud and mud fluid or water are thrown over the entire derrick floor, thus creating a very dangerous condition which has in many instances resulted in serious injury to workmen, due to the fact that workmen have not had a secure footing on the derrick floor. In my invention the rotary mud which may fall onto the upper face of the rotary table 29 when thrown outwardly therefrom, as indicated by the arrows 108, passes, as indicated by arrows 109, into the space 97 and is thereafter caused to flow through this space 97 into the vertical space 102, thus being deflected downwardly and thus being prevented from continuing in an outward direction and ultimately falling over the entire derrick floor or a part thereof.

I have found by experiment that when the rotary mud is relatively thin and the revolutions per minute of the rotary table are relatively high, the force applied to the rotary mud or mud fluid is so great that the rotary mud continues to move in a spiral or twisting path in the space 97 and the vertical space 102, and upon passing from the lower part of the space 102 tends to continue to move outwardly. I have therefore found that it is desirable to guard against such a contingency by providing the fins 106 which serve to effectively deprive the rotary mud or mud fluid of all of its spiral or twisting motion, thus entirely relieving the rotary mud of all of its energy which tends to cause it to move outwardly from the rotary machine. The rotary mud or mud fluid having no such energy will therefore fall downwardly from the vertical space 102 and by the action of gravity drop onto the base 11 or the immediately adjacent part of the derrick floor.

In the event that any of the mud fluid enters the space between the table top and the base casting 11 and has a tendency to flow upwardly and inwardly through the inverted U-shaped passage 70 of the mud seal 58, this mud will upon reaching the bottom of the groove 54 fall downwardly through the vertical passages 18 provided in the rim 17. It will be seen that none of the rotary mud or mud fluid or water can penetrate to the interior of the machine to adulterate the lubricating fluid contained in the oil reservoir 23. This is a particularly valuable feature inasmuch as it is the usual practice while "washing down" to direct a high pressure water stream against the rotary machine and upon the derrick floor. During this "washing down" operation the water can penetrate only as far as the bottom of the groove 54 and will then be drained therefrom by the passages 18.

I believe my invention to be broadly contained in the principles which I have developed, and therefore I wish my invention to be construed in accordance with the spirit and scope thereof and in accordance with the appended claims.

I claim as my invention:

1. In a rotary machine of the type employed in the drilling of oil wells, the combination of: a base; a rotary table; bearing means whereby said rotary table is rotatably supported on said base; drive means whereby said rotary table is rotated; and an annular upstanding wall surrounding said

rotary table for diverting the fluid which is thrown outwardly from the upper surface of said rotary table.

2. In a rotary machine of the type employed in the drilling of oil wells, the combination of: a base; a rotary table; bearing means whereby said rotary table is rotatably supported on said base; drive means whereby said rotary table is rotated; and means for preventing fluid from being thrown outward a material distance beyond the upper surface of said rotary table, said last named means including wall means for restraining the outward travel of said fluid and for restraining the spiral motion thereof.
3. In a rotary machine of the type employed in the drilling of oil wells, the combination of: a base; a rotary table; bearing means whereby said rotary table is rotatably supported on said base; drive means whereby said rotary table is rotated; an annular upstanding wall surrounding said rotary table for preventing fluid from being thrown outward a material distance beyond said rotary table; and a plurality of fins for restraining said fluid from a spiral motion.
4. In a rotary machine of the type employed in the drilling of oil wells, the combination of: a base; a rotary table; bearing means whereby said rotary table is rotatably supported on said base; drive means whereby said rotary table is rotated; a cylindrical wall surrounding said rotary table; an annular flange extending inwardly over said rotary table; and fin means extending inwardly from said cylindrical wall.
5. In a rotary machine of the type employed in the drilling of oil wells, the combination of: a base; a rotary table; bearing means whereby said rotary table is rotatably supported on said base; drive means whereby said rotary table is rotated; a cylindrical wall surrounding said rotary table; an annular flange extending inwardly over said rotary table; and a plurality of axial fins extending into a passage formed within said cylindrical wall.
6. In a rotary machine of the type employed in the drilling of oil wells, the combination of: a base having an upstanding wall; a rotary table cooperating with said base to form a closed chamber; bearing means whereby said rotary table is rotatably supported; a separate annular rim surrounding said upstanding wall, there being an annular channel between said upstanding wall and said annular rim; and an annular ridge extending downwardly from said rotary table into said annular channel.
7. In a rotary machine of the type employed in the drilling of oil wells, the combination of: a base having an upstanding wall; a rotary table cooperating with said base to form a closed chamber; bearing means whereby said rotary table is rotatably supported; an annular rim surrounding said upstanding wall, there being an annular channel between said upstanding wall and said annular rim, said channel being open at the upper and the lower parts; and an annular ridge extending downwardly from said rotary table into said annular channel.
8. In a rotary machine of the type employed in the drilling of oil wells, the combination of: a base having an upstanding wall; a rotary table cooperating with said base to form a closed chamber; bearing means whereby said rotary table is rotatably supported; a separate annular rim surrounding said upstanding wall, there being an

annular channel between said upstanding wall and said annular rim; an annular ridge extending downwardly from said rotary table into said annular channel; and a depending flange carried by said rotary table outside said annular rim.

9. In a rotary machine of the type employed in the drilling of oil wells, the combination of: a base having an upstanding wall; a rotary table cooperating with said base to form a closed chamber; bearing means whereby said rotary table is rotatably supported; an annular rim surrounding said upstanding wall, there being an annular channel between said upstanding wall and said annular rim, said channel being open at the upper and the lower parts; an annular ridge extending downwardly from said rotary table into said annular channel; and a depending flange carried by said rotary table outside said annular rim.

10. In a rotary machine of the type employed in the drilling of oil wells, the combination of: a base having an upstanding wall; bearing means; a rotary table rotatably supported by said bearing means, said base and said rotary table cooperating to provide a lubricant chamber; and sealing means for said lubricant chamber including a depending wall on said rotary table projecting downwardly inside said upstanding wall, and a shoulder extending inwardly from said upstanding wall below said depending wall, there being drain means connected to the upper part of said shoulder.

11. In a rotary machine of the type employed in the drilling of oil wells, the combination of: a base having an upstanding wall; bearing means; a rotary table rotatably supported by said bearing means, said base and said rotary table cooperating to provide a lubricant chamber; and sealing means for said lubricant chamber including a depending wall on said rotary table projecting downwardly inside said upstanding wall, said depending wall having a bead formed at the lower end thereof, and a shoulder extending inwardly from said upstanding wall below said depending wall, there being drain means connected to the upper part of said shoulder.

12. In a rotary machine of the type employed in the drilling of oil wells, the combination of: a base having an upstanding wall; bearing means; a rotary table rotatably supported by said bearing means, said base and said rotary table cooperating to provide a lubricant chamber; and sealing means for said lubricant chamber including a depending wall on said rotary table projecting downwardly inside said upstanding wall, said depending wall having a bead formed at the lower end thereof, and a shoulder extending inwardly from said upstanding wall below said depending wall, the upper face of said shoulder forming a channel into which said bead extends, there being drain means connected to the upper part of said shoulder.

13. In a rotary machine of the type employed in the drilling of oil wells, the combination of: a base; a rotary table rotatably supported on said base, said rotary table having an exterior surface onto which fluid may pass; drive means for rotating said rotary table; and means providing a space around said rotary table into which said fluid is thrown by centrifugal force and forming a barrier for diverting said fluid being thrown outwardly from said rotary table.

14. In a rotary machine of the type employed in the drilling of oil wells, the combination of: a base; a rotary table rotatably supported on said base, said rotary table having an exterior surface onto which fluid may pass; drive means for ro-

tating said rotary table; means providing a space around said rotary table into which said fluid is thrown by centrifugal force for preventing said fluid from being thrown outwardly from said rotary machine; and means in said space for arresting the spiral motion of said fluid.

5. 15. In a rotary machine of the type employed in the drilling of oil wells, the combination of: a base having an upstanding wall; a rotary table 10 rotatably supported on said base, said upstanding wall and said table cooperating to provide a lubricant chamber; drive means in said lubricant chamber for rotating said table; and a shoulder extending inwardly from said upstanding wall 15 near the proximate portions of said upstanding wall and said table, there being a drain passage in said shoulder.

16. In a rotary machine of the type employed in the drilling of oil wells, the combination of: a base having an upstanding wall; a rotary table 20 rotatably supported on said base, said upstanding wall and said table cooperating to provide a lubri-

cant chamber, said upstanding wall and said table having proximate portions providing a space into which lubricant in said lubricant chamber is crowded by centrifugal force; and walls forming a drain passage connected so as to drain lubricant from said space back into said lubricant chamber.

17. In a rotary machine of the type employed in the drilling of oil wells, the combination of: a base having an upstanding wall; a rotary table 10 rotatably supported on said base, said upstanding wall and said table cooperating to provide a lubricant chamber, said upstanding wall and said table having proximate portions providing a space into which lubricant in said lubricant chamber is 15 crowded by centrifugal force; and walls forming a drain passage connected at one end to said space so that the lubricant crowded in said space may flow into said drain passage, and connected at its other end to deliver said lubricant to said lubricant chamber.

DAVID M. SMITH.
